CLAIM

I claim the ornamental design for a lighted opaque display, as shown and described.

DESCRIPTION

FIG. 1 is a front elevational view of the lighted opaque display from a viewpoint perpendicular to the front panel.

FIG. 2 is a top view of the lighted opaque display shown in FIG. 1.

FIG. 3 is a bottom view of the lighted opaque display shown in FIG. 1.

FIG. 4 is a left side view of the lighted opaque display shown in FIG. 1 from a viewpoint perpendicular to the left side panel; and,

FIG. 5 is a right side view of the lighted opaque display shown in FIG. 1 from a viewpoint perpendicular to the right side panel.
